CLAIM

The ornamental design for a tote box, as shown and described.

DESCRIPTION

FIG. 1 is a front, top perspective view of a tote box showing my new design;

FIG. 2 is a rear, top perspective view thereof;

FIG. 3 is a front, bottom perspective view thereof;

FIG. 4 is a top elevational view thereof;

FIG. 5 is a front side elevational view thereof;

FIG. 6 is a rear side elevational view thereof;

FIG. 7 is a left end plan view thereof, the right end plan view being a mirror image of this; and,

FIG. 8 is a bottom elevational view thereof.

The broken line representations of holes and handle structures in FIGS. 1-4, 7 and 8 are exemplary and form no part of the claimed design.
